UNITED STATES PATENT OFFICE.

MORTIMER E. COOLEY, OF ANN ARBOR, MICHIGAN.

VENTILATING SYSTEM.

SPECIFICATION forming part of Letters Patent No. 783,616, dated February 28, 1905.

Application filed May 11, 1903. Serial No. 156,712.

To all whom it may concern:

Be it known that I, MORTIMER E. COOLEY, a citizen of the United States, residing at Ann Arbor, in the county of Washtenaw and State 5 of Michigan, have invented certain new and useful Improvements in Ventilating Systems; and I do hereby declare the following to be a full, clear, and exact description of the invention, such as will enable others skilled in the 10 art to which it appertains to make and use the same.

This invention is a system for controlling the ventilating of buildings.

It is particularly adapted to buildings having 15 a large number of rooms to be ventilated for varying lengths of time, such as school-buildings and hospitals, where rooms are used and then unoccupied for shorter or longer periods of time.

20 My invention provides a ventilating system having the following important advantages: The ventilation of all the rooms or any individual room or group of rooms is brought under the control of a responsible attendant at 25 a central station so that he can establish ventilation in any room shortly before the schedule-time for it to be occupied and can check the ventilation as soon as the room is vacated, thereby saving the heat required to warm the 30 ventilating-air during the time the room is unoccupied.

Means are provided at the central station whereby the dampers of a single room or of 35 several rooms can be manipulated without disturbing the dampers of the remaining rooms.

My invention is illustrated in the accompanying drawings, in which—

Figure 1 is an elevation, partly in section, of part of a building using my improved system. Fig. 2 is a horizontal cross-section of the flues. Fig. 3 is an elevation, partly in section, showing the method of operating the dampers. Fig. 4 is a perspective view of a system of valves and headers for controlling 45 the dampers. Fig. 5 is a longitudinal section through the three-way valve 14.

To better illustrate the application of my controlling means to a modern building, I have selected one in which the upright ventilating-flues in the walls of the building are 50

arranged in parallel rows, so that the lower part of a flue may be used as a fresh-air inlet for one of the lower rooms, the upper part of the same flue being used as a foul-air outlet for the room above. The foul air is carried away 55 from the lower room by a second flue, and fresh air is supplied to the upper room by a third flue. A partition 2 in the flue 1 separates the fresh air below from the foul air above. The foul air is usually discharged 60 into a main foul-air conduit 3 and then passes outside the building.

While I wish to describe my invention as applied to the arrangement of ventilating-flues shown in Fig. 1, it will be understood 65 that it may also be employed in connection with any other suitable flue arrangement.

In the building illustrated in Fig. 1 the fresh air that has previously been tempered by any suitable means enters each room through 70 a register 4 near the ceiling, and the foul air is discharged through a register 5 near the floor. Each fresh-air flue has a damper 6, and each foul-air flue has a damper 7. Where the flue arrangement is such as to permit, 75 the fresh-air and foul-air dampers for each room are preferably fixed to a common rock-shaft 8, so as to open and close together. By closing the dampers 6 and 7 for any given room the circulation of air for ventilation 80 through that room can be stopped. In school-buildings, hospitals, &c., certain rooms are unoccupied for longer or shorter periods of time each day, and if the circulation of air through an unoccupied room be stopped the 85 heat required to warm the air for ventilation will be saved. This heat, which of course represents fuel expense, would otherwise be wasted.

To provide means for starting or stopping 90 circulation at will and to place under the positive control of one operator at a central station the ventilation of all the rooms of a building is, as stated above, the object of my invention.

I operate the dampers 6 and 7 by means of fluid under pressure, and I prefer to employ compressed air for the purpose, although water, oil, or other fluid may be used. The mechanism by which the dampers are actu- 100

ated may be any of the suitable well-known constructions now in common use; but for the purpose of illustration I have represented diagrammatically one type of such a device in Fig. 3. This mechanism consists in a pressure-chamber 9, closed by a flexible diaphragm 9^a. The diaphragm is connected by a lever 10 and a link 11 to one of the dampers 6 or 7 or to a lever-arm on their common shaft. Fluid under pressure is supplied to the chamber 9 by the pipe 12 to lift the diaphragm 9^a, and so actuate the dampers. The upward movement of the lever is resisted by a spring 13, which returns the dampers to their original position when the pressure in the chamber is relieved. The lever may be connected to the dampers in the manner indicated by full lines in Fig. 3, so that pressure below the diaphragm will open the dampers. In some buildings it is inconvenient to operate both the fresh-air and foul-air dampers of a room by a single pressure device. Each damper may then have its own operating mechanism, and they may be arranged to operate independently or conjointly.

The pressure-supply pipes 12 for all the damper-actuators are brought to the central station in the basement or other convenient place, as shown in Fig. 1, and are there connected to a common receptacle or header H, supplied with fluid under pressure. The source of pressure is immaterial; but if compressed air is used an air-compressor may be installed in any convenient location and connected to header H by a supply-pipe P. The source of compressed air is omitted from the drawings for the sake of clearness. The branch supply-pipe 12 to each damper-actuator has a three-way valve 14 or its equivalent, by which the pipe 12 may be opened to the header to receive pressure or closed to the header and opened to the atmosphere to relieve pressure. The two ventilating-flues of any room can thus be opened or closed by simply turning the proper valve 14. In the main pressure-supply pipe P a similar valve 15 is provided, whereby pressure may be admitted to or removed from the header H and from all the damper-controllers simultaneously, thereby inducing or checking ventilation in all the rooms at once. Thus the ventilation in each room is controlled by an operator at a central station, either in the building or at a reasonable distance outside. A time-schedule for the ventilation of the different rooms is provided for his guidance. Inspection of this schedule tells him what rooms are in use and what are unoccupied. By opening the proper valves 14 he opens the dampers and starts the circulation of ventilating-air through the rooms where ventilation is needed and by closing the valves stops the circulation through the rooms when they are unoccupied. This combination of header, pressure-pipes, and double-service or three-

way valves makes it possible to easily cut out rooms in any part of the building for an hour at a time, whereas if the operator were required to go to each room to open or close the dampers it is probable that those rooms which were to be out of service for only a short time would not be cut out, and the expense of maintaining ventilation in them while unoccupied would be a total loss.

It occasionally happens that ventilation is required in only one or two rooms of a building containing a large number of apartments. If the entire building is being ventilated it is inconvenient to cut out each of the other rooms individually, even by the simple three-way or equivalent means which I have just described. To overcome this inconvenience and to permit all of the rooms except a few to be quickly cut out without manipulating each valve 14 separately, the form of operating system illustrated in Fig. 4 is provided. In this arrangement two headers H' and H" are employed, each having a main fluid-pressure pipe P' and P" and three-way valves 15' and 15", by which fluid under pressure is admitted to the headers or by which the headers can be closed to pressure and opened to the atmosphere. The branch supply-pipes 12 are connected to both headers by three-way valves 14. Any pipe may be opened to either header and closed to the other by turning its valve. Thus with the pipes 12 all open to the header H' if the dampers are connected to their actuating devices, as shown by full lines in Fig. 3, admitting pressure to the header H' opens all the dampers in the building simultaneously. If it is required to check ventilation in any room, open the header H" to atmosphere by means of valve 15" and open the proper controlling-valve 14 to the header H". This leaves all the other dampers open to ventilate their respective rooms. Suppose now that it is desired to suddenly reverse the conditions by shutting off all the rooms now being ventilated and to ventilate the room now shut off. The change can quickly and easily be made as follows: Open valve 15', thereby releasing pressure in header H' and closing all the open dampers simultaneously. Then admit pressure to header H" by valve 15", thus opening the dampers of the room that was previously cut out. Only two valves have been moved. A very great number of combinations are possible with this arrangement, and any desired changes in ventilation can be made at the central station with the least possible manipulation.

In practice with school-buildings, the room being ventilated only a few hours of the day, it will be better to have the dampers closed by the springs 13 or equivalent means and opened by fluid-pressure, thereby keeping diaphragms 9^a from pressure most of the time, prolonging their life and saving fluid from possible leakage. In hospitals, with rooms

5 ventilated most of the time, the reverse will be true, and the dampers should then be held open by springs 13 and closed by fluid-pressure. The combination, Fig. 4, admits of doing this with minimum trouble, and it likewise admits of other combinations that might be desired, as in the following case: First, let H' and H'' both be under pressure and three-way valves 14 open to H'. Then all dampers 10 are opened (or closed). Now release pressure in H' by opening 15 to atmosphere, and all dampers are closed (or opened). Second, if desired, any damper may now be opened (or closed) by turning its valve 14 so as to place 15 12 in communication with H'' and later may be closed (or opened) by turning 14 back again to H'.

This system for centrally controlling ventilation is easily installed and easily operated. 20 The apparatus controlling the ventilation of an entire building may be located in a small room to which none but authorized persons have access. A schedule of the rooms and the hours in which they are occupied may be prepared, and the circulation of air through each unoccupied room may be stopped as soon as the room is out of service and started again when the room is needed. In this way a large saving in heat is effected. 25 30 While I have throughout this specification referred to the damper-actuating medium as "fluid under pressure," I wish it to be understood that I employ the word "pressure" as a relative term and do not confine myself to the use of pressure greater than atmosphere, 35 for it is evident that a mere reversal of pres-

sures—as, for instance, subjecting the headers to partial vacuum instead of to compressed air—might be made to serve the purpose of opening and closing the dampers in accordance with my invention. 40

What I claim as my invention, and desire to secure by Letters Patent, is as follows:

1. In a ventilating system for buildings having rooms each provided with a fresh-air flue 45 and a foul-air flue, dampers in said flues, and a fluid-operated damper-actuator; a source of fluid under pressure; a header communicating with said source; a three-way valve for controlling communication between the header 50 and said source; conduits connecting the header with each damper-actuator; together with a three-way valve in each conduit; said three-way valves being grouped at a central station, for the purpose set forth. 55

2. In a ventilating system for buildings having rooms each provided with a fresh-air flue and foul-air flue, dampers in said flues, and a fluid-operated damper-actuator; a source of fluid under pressure; a pair of headers communicating with said source; a three-way valve for controlling communication between each header and said source; pipes connecting the two headers; a conduit connecting one of said pipes with each damper-actuator, together with a three-way valve in each conduit. 60 65

In testimony whereof I affix my signature in presence of two witnesses.

MORTIMER E. COOLEY.
